N. Beckmann, both of San Antonio, Tex., co-
partners doing business as Birkhead, Beck-
mann, Stanard & Vance

Application August 17, 1938, Serial No. 225,487

2 Claims. (Cl. 158—115)

This application is a continuation in part of my U. S. patent application which has matured in U. S. Patent No. 2,152,531 of March 28, 1939, covering a Gas stove burner mechanism and 5 igniting means.

The invention aims to provide a new and improved arrangement of elements for lighting a burner of a gas stove, or other gas burner, by means of an igniting burner, the latter being 10 automatically lighted electrically when a gas-controlling valve member is moved to a predetermined position.

A further object is to make novel provision whereby either a main or an auxiliary burner 15 may be lighted by means of the electrically lighted igniting burner.

Yet another object is to provide a novel electric switch mechanism for controlling the ignition circuit utilized to effect lighting of the igniting 20 burner.

With the foregoing in view, the invention resides in the novel subject matter hereinafter described and claimed, description being accomplished by reference to the accompanying 25 drawings.

Fig. 1 is a top plan view partly in horizontal section.

Fig. 2 is a side elevation partly in vertical section.

Fig. 3 is a diagram cutting through the burner on line 3—3 of Fig. 1 and showing the switch mechanism as viewed on line 3—3 of Fig. 2, said switch mechanism being shown diagrammatically connected with the electrodes over the igniting burner and with an induction coil and source of current, such as a battery.

Fig. 4 is a fragmentary front elevation showing the knob for controlling the movable valve member and the ignition switch, and preferable legs 40 ends for coaction with said knob.

Fig. 5 is a transverse sectional view through the gas-controlling valve, substantially on line 5—5 of Fig. 2.

Figs. 6 and 7 are views similar to Fig. 5 but showing different positions of the rotatable valve member.

Preferred features of construction have been shown in the drawings for illustrative purposes, and while they will be rather specifically described, it is to be understood that variations may be made within the scope of the invention as claimed.

A main burner 8 and an auxiliary or simmer burner 9 are shown in concentric relation with 55 each other, and within the confines of said burner 9 I have shown a perforated hood 10 under which two electrodes 11 and 12 are mounted, said electrodes being directly over an igniting burner 13. Two gas passages in the 60 conduit member 14, extend to the burners 8 and 9

respectively, and a separate conduit 15 is shown for the igniting burner 13. The outer ends of these conduits 14 and 15 are provided with suitable valved air inlets which are indicated at 16 in Fig. 2, and gas is admitted into the inlet 5 passages of the three burners through appropriate nipples 17 connected with short pipes 18, 19 and 20, these pipes being connected with discharge nipples 21, 22 and 23 on the body or casing 10 of a gas-controlling valve 24, this body being provided with a gas inlet nipple 25 communicating with the usual range manifold or the like 15 26. A tapered valve plug 27 is rotatable within the valve casing and is provided with an operating stem 28 extending through the front plate 29 of the range or the like and provided with an operating knob 30. The plug 27 is provided with a central gas-receiving chamber 31 and with four radial ports 32, 33, 34 and 35 communicating with said chamber and extending to 20 the periphery of the plug for coaction with the nipples 21, 22, 23 and 25.

The plug 27 may be turned to any of seven 25 positions, one of which is a fully closed position, shown in Fig. 5. When the plug is turned to the right to one open position (Fig. 6) gas will flow from the nipple 25 through the port 32 into the chamber 31, and from this chamber through the port 34 to the nipple 21, from which it will pass on to the igniting burner 13. When the 30 plug is turned to the right to a second open position (between the positions shown in Figs. 6 and 7), gas will continue to flow to the igniting burner 13 and at the same time, the port 33 will be partially in communication with the nipple 23, 35 so that gas will flow also to the main burner 8. When the plug 27 is turned still further to the right to a third open position, it conducts gas only from the nipple 25 to the nipple 23 as seen in Fig. 7, thus continuing the supply of gas to 40 the burner 8 and extinguishing the ignition burner 13. The plug 27 is also turnable to the left to three positions, the first of which places the nipple 25 in communication with the nipple 21 to direct gas to the igniting burner 13. The 45 second position is one in which gas continues to flow to the igniting burner 13 and also flows to the simmer burner 9 to ignite the latter, and the third position is one in which gas continues to flow to the simmer burner but is cut off from the 50 igniting burner.

The seven positions above described, of the 55 plug 27, are preferably indicated on the front plate 29 for coaction with the knob 30, as seen in Fig. 4.

Provision is made for causing a spark to jump between the electrodes 11 and 12 when the knob 30 is turned to turn the plug 27 to either of the 60 positions in which it directs gas to the igniting burner 13, thereby lighting this burner, and when 65

the knob is turned further to light either the simmer burner 9 or the main burner 8, the current for the spark gap is, of course, broken and after initial lighting of said burner 9 or said 5 burner 8, further turning of the knob to burner-operating position will, of course, cut off the flow of gas to the igniting burner 13. When turning the knob 30 back to "off" position, a small quantity of gas may again be discharged into the 10 igniting burner 13, but such turning of said knob will again cause a spark to jump between the electrodes 11 and 12 so that this gas will be consumed instead of discharging into the room.

For controlling the supply of current to the 15 electrodes 11 and 12, I preferably employ the switch means now to be described, and said switch means completes both the primary and secondary circuits of an induction coil 36 when the valve member 27 is turned to either of the 20 "light lighter" positions, to effect ignition of the gas discharged from the burner 13.

An insulating plate 37 is secured to the stem 28 of the valve member 27. At one side of this plate 37 is a metal plate 38 having two contacts 39 passing through said plate 37, said contacts 39 being selectively cooperable with a spring-pressed contact 40 on a conducting strip 41 suitably mounted behind the plate 29. Also carried by the plate 37 are two angle plates 42 having 30 contacts 43, either of which is cooperable with a spring-pressed contact 44 on another conducting strip 45 mounted under the strip 41. Another contact 46 is cooperable with either of the plates 42, said contact 46 being suitably mounted behind 35 the plate 29. Normally, with the valve in "off" position (Figs. 4 and 5), the plate 37 occupies the position shown in Fig. 3 with the contacts 39 spaced equally at opposite sides of the contact 40, and the contacts 43 spaced equally at opposite sides of the contact 44, the plates 42 being then also equally spaced from the fixed contact 46.

A conductor 47 leads from the strip 41 to the primary winding of the induction coil 36, which 45 coil includes the customary vibrator 48 and condenser 49. Another conductor 50 leads from the strip 45 to the secondary coil or winding of the induction coil 36, and a conductor 51 leads from the contact 46 to the electrode 11. The electrode 12 is grounded as indicated at 52, one pole of the battery or other current source 53 is grounded as indicated at 54, and one end of the secondary winding of the ignition coil 36 is also grounded as at 55, the various ground connections 55 52, 54 and 55 being of course to metal parts of the stove or the like. The plate 38 is also grounded to these metal parts, by means of a rivet 56 passing through the hub of the plate 37 and through the stem 28 of the valve plug 27.

60 From the above, it will be seen that turning of the knob 30 to either "light lighter" position, will complete both the primary and secondary circuits for the induction coil 36, causing the secondary to jump between the electrodes 11 and 12 to effect ignition of the gas discharged from the burner 13. It will also be clear that further turning of the knob 30 either to the "light burner" position or the "light simmer" position, will again break both the primary and secondary circuits.

70 It is a simple matter to effect lighting of either burner desired, simply by turning the knob 30 to the proper position for an instant, and then turning it on to the proper burner-operating po-

sition. The first movement effects automatic lighting of the burner 13, further movement causes lighting of one or the other of the burners 8, 9, while the burner 13 is still in operation, and still further movement extinguishes the burner 5 13 and admits the gas only to the burner 8 or 9 as the case may be. When the knob 30 is turned back to "off" position, some gas will pass to the burner 13 during this movement, but it will be observed that this movement also causes another spark to jump between the electrodes 11 and 12, so that this gas which would otherwise leak into the room, will be burned.

Excellent results may be obtained from the general construction shown and described and this 15 construction is, therefore, preferably followed. However, within the scope of the invention as claimed, variations may be made as above stated.

I claim:

1. A valve for directing gas to a main burner, 20 to an auxiliary burner and to an igniting burner for said main and auxiliary burners; said valve comprising a body having a gas admission port, a main burner feed port, an auxiliary burner feed port, and an igniting burner feed port; and 25 a manually rotatable plug in said body normally occupying a neutral position in which all of said ports are closed, said plug having ports operable when said plug is turned in one direction from a neutral position to first place only said igniting 30 burner feed port in communication with said admission port, to then place both said igniting burner feed port and said auxiliary burner feed port in communication with said admission port, and to finally place only said auxiliary burner 35 feed port in communication with said admission port; said plug having additional ports operable when said plug is turned in the other direction from said neutral position to first place only said igniting burner feed port in communication with 40 said admission port, to then place both said igniting burner feed port and said main burner feed port in communication with said admission port, and to finally place only said main burner feed port in communication with said admission port. 45

2. A valve for directing gas to a main burner, to an auxiliary burner and to an igniting burner for said main and auxiliary burners; said valve comprising a body having a gas admission port, a main burner feed port, an auxiliary burner feed port, and an igniting burner feed port; and 50 a manually operable member in said body normally occupying a neutral position in which all of said ports are closed, said member having ports operable when said member is moved in one direction from a neutral position to first place only said igniting burner feed port in communication with said admission port, to then place both said igniting burner feed port and said auxiliary burner feed port in communication with said admission port, and to finally place only 55 said auxiliary burner feed port in communication with said admission port; said member also having ports operable when said member is moved in the other direction from said neutral position to first place only said igniting burner feed port in communication with said admission port, to then place both said igniting burner feed port and said main burner feed port in communication with said admission port, and to finally place 60 only said main burner feed port in communication with said admission port. 65

JAMES E. BROWNING.
